UNITED STATES PATENT OFFICE.

GUSTAV A. NAUMANN, OF ST. LOUIS, MISSOURI.

IMPROVEMENT IN JOINERS' CLAMPS.

Specification forming part of Letters Patent No. 178,022, dated May 30, 1876; application filed April 11, 1876.

To all whom it may concern:

Be it known that I, GUSTAV A. NAUMANN, of St. Louis, Missouri, have invented an Improvement in Joiners' Clamps, of which the following is a specification:

This invention is an improvement on patents issued to me dated and numbered, respectively, October 19, 1875, No. 169,027, and March 14, 1876, No. 174,838.

Of the drawing, Figure 1 is a sectional elevation, showing the parts locked. Fig. 2 is a bottom plan of top plate with its operating parts in open or unlocked condition. Fig. 3 is a detail view of manner of fastening the front screw, Fig. 4 being a side elevation of the key used to operate the slides.

A and B are the fixed and movable jaws, respectively. C and C' are the front and rear hand-screws, respectively. D and D' are front and rear slides, which are to clamp the hand-screws. These slides are similar in construction, each having a nut-shaped portion with screw-threads corresponding to the threads of the hand-screws, and as shown in Fig. 1. The action and movement of the slides D D' is similar as in my last patent referred to; but the parts that operate said slides constituting my present improvement are as follows: Besides the threaded portion of the slides D D', I construct the remaining part thereof to each present the hook-shaped shanks d and d'. (See Fig. 2.) The space between the hook ends d and d' is adapted to admit of a turn-key, d², cross-shaped or double-armed in construction, and as shown in Figs. 1, 2, and 4. d³ d⁴ (see Fig. 4) are the arms of the key, acting or turning in the space left between the two hooks of the slides, and consequently forcing said slides apart in opposite directions. E is a spring, (see Figs. 1 and 2,) which serves to return the slides to original position.

To retain my operating parts a cover-plate, F, is screwed down upon the top of the jaw and over the operating parts, said cover having proper opening for the hand-screws, and also a slot, f, for the play of the key. The hand-screws have their threads reversed, as formerly.

The securing of the hand-screws in the lower jaw is as follows—the object being to secure

the screws as firmly as possible, and at same time not weaken unnecessarily the jaw: The front screw, when any article is clamped, tends to draw out or unloosen its hold in the lower jaw, while the strain of the other hand-screw is downward. In my present joint I pass the forward screw, say, about two-thirds into the jaw, and hold it in position by a staple, f¹, which engages around the neck of the screw end, said staple having a broad bearing-surface, to act against the solid material above. (See Fig. 3.) The rear screw need only then to have a joint with the lower jaw sufficient to prevent said screw disengaging or slipping out of its place, and giving it as much solid bearing below as possible. For this purpose I merely pass a pin, f², through the jaw, to engage the neck end of the screw. (See Fig. 1.)

Thus constructed and arranged, the operation of the parts is as follows: The parts being in locked position, (see Fig. 1,) the key d² is on a cross-line with relation to the position of the hook ends or slides proper. To disengage the movable jaw from adjustment, the key is therefore turned, say, a quarter-turn, to the right; its arms d³ d⁴, engaging the hook end of the slides, force same in opposite directions away from the hand-screws, and assume the unlocked position shown in Fig. 2. In this position the key has its arms parallel with the slides, and is at a dead-point; and having compressed the spring E, the movable jaw is sufficiently loosened to be adjusted to required positions along the hand-screws. To secure the movable jaw in adjusted position, the key is turned so as to come to the position shown in Fig. 1, which enables the compressed spring to relock the slides in engagement with the hand-screws, and as indicated in Fig. 1.

The advantages achieved by this construction and operation of the parts (over my former patents) are, that the operation is more reliable, the clamp decisively and solidly holding the article. The adjustment of the movable jaw is greatly facilitated, and is positive by its slides in disengaging and engaging the threads; besides, the construction here shown and described is far more simple, easier made, and cheaper. In use, the clamp-screw is much more durable, stronger, and effective in its

parts, for it will be noted that the greater solid portion of the jaw is retained—an advantage of great importance in machines of this nature.

What I claim is—

The turn-key d^2 , having arms $d^3 d^4$, the slides D D', having hook-shanks d^1 , the spring E, plate or cover F, having slot f, in combination with movable jaw B, right-and-left screws C

C', and stationary jaw A, arranged to operate in the manner and for the purpose set forth.

In testimony of said invention I have hereunto set my hand.

GUSTAV A. NAUMANN.
